COMBINED CAMERA AND FLASH GUN

Richard J. Olson, Lima, and Frank A. Zagara, Rochester,
N.Y., assignors to Eastman Kodak Company, Roches-
ter, N.Y., a corporation of New Jersey

Filed Mar. 23, 1962, Ser. No. 69,393

Term of patent 7 years

(Cl. D61—1)

Fig. 1

Fig. 2

Fig. 3

Fig. 4

FIG. 1 is a front perspective view of a combined camera and flash gun, showing our new design with the flash door in closed position;

FIG. 2 is a front perspective view thereof, with the flash door in an open position;

FIG. 3 is a rear perspective view thereof, showing the back and top; and

FIG. 4 is a bottom perspective view thereof, showing the bottom and back.

We claim:

The ornamental design of a combined camera and flash gun, as shown.
